UNITED STATES PATENT OFFICE.

CHESTER C. CLELAND, OF CLEVELAND HEIGHTS, AND JOHN C. MULLINNIX, OF CLEVELAND, OHIO, ASSIGNORS TO THE RELIANCE GAUGE COLUMN COMPANY, OF CLEVELAND, OHIO, A CORPORATION OF OHIO.

METHOD OF MAKING METALLIC FLOATS.

Application filed November 14, 1924. Serial No. 749,841.

To all whom it may concern:

Be it known that we, CHESTER C. CLELAND and JOHN C. MULLINNIX, citizens of the United States, and residents of Cleveland Heights and Cleveland, county of Cuyahoga, State of Ohio, respectively, have jointly invented a new and useful Improvement in Methods of Making Metallic Floats, of which the following is a specification, the principle of the invention being herein explained and the best mode in which we have contemplated applying that principle so as to distinguish it from other inventions.

The present improvements relate more particularly to metallic floats such as are employed in steam traps, water columns and the like. A preferred method for making such floats is by electro-plating a suitable hollow foundation since thereby an external seamless metallic coat or coating is secured. However, due to the fact that such an electro-plated coating is substantially uniform, a difficulty has been encountered in thus making floats of oblong form in contradistinction to spherical or substantially spherical form. In the case of floats of such last mentioned form, it is of course desirable that metal composing the shell of the float should be of uniform thickness; however, in the case of a float of elongated form, the more or less straight side portion requires to be reinforced in order to withstand the compression strains to which the float is subjected in service, or else if the shell is made of uniform thickness throughout, the ends will include much more metal than is necessary.

In the case of oblong floats made by assembling two half shell portions, it has been customary to reinforce the sides by soldering or otherwise fixedly attaching an encircling band to the float midway between its ends. By our present improved method of manufacture, we provide for an integral reinforcement of the sort described by electro-depositing an extra thickness of metal about such intermediate side portion of the float. This is done incidentally to the electro-plating of the float in its entirety and so does not require any additional operation, while by thus integrally incorporating in the shell the additional metal required to give the necessary resistance to compression

strains, a much more durable as well as better appearing float is produced.

To the accomplishment of the foregoing and related ends, the invention, then, consists of the means and steps hereinafter fully described and particularly pointed out in the claims, the annexed drawing and the following description setting forth in detail one method and one product exemplifying our invention, such disclosed procedure and product constituting, however, but one of various applications of the principle of our invention.

In said annexed drawing:—

Fig. 1 illustrates more or less diagrammatically an electrolytic bath with a float of the type in question suspended therein so as to receive a coating of graduated thickness such as described above; and Fig. 2 is an axial section of such float in finished form.

The core 1 (see Fig. 2), upon which the metallic shell or coating requires to be electro-deposited, is of the oblong form which it is desired the finished article should have. Such core, in other words, consists of substantially hemispherical ends connected by an intermediate cylindrical portion and may be made out of any suitable material, as for example celluloid, molded wood pulp, or the like. It will be understood, of course, that the exterior surface of the core will be suitably prepared so that when such core is immersed in an electrolytic bath, as shown in Fig. 1, and a suitable electric current is passed through such bath from a metallic electrode 2 to the core, the desired metal will be deposited on the core.

In order properly to suspend the core in the bath, as well as for the purpose of attaching to the same when completed a suitable stem, a nipple 3 is attached to one end of said core by means of a spud 4, the latter being formed to seat in an aperture 5 in such end such as is necessarily left where the core is of molded plastic material. There will also be superficially attached to the other end of the core a second nipple 6, similar to nipple 3, said nipple 6 being utilized merely in the electro-plating operation, as will now be explained.

The core is suspended in the bath by means of a stem 7 of good conducting material through which electric connection is

had, such stem initially having threaded engagement with either nipple 3 or 6 indifferently. It will be understood that the stem is rotatably supported and that it will be provided at its upper end with a pulley 8 or equivalent means, whereby it, together with the attached core, may be rotated about their common axis. The core will be thus suspended, as clearly shown in Fig. 1, so that the upper hemispherical end will lie above the normal level of the liquid composing the bath and the coating initially deposited on the core will hence extend over the lower hemispherical end and the intermediate cylindrical portion only. After a short interval, however, the core is detached from stem 7 and its position reversed, the stem now being engaged with the opposite nipple whereupon the electro-plating operation is resumed. As a result, the hemispherical end that previously projected above the level of the bath will now receive an initial metallic coat, while the intermediate cylindrical portion will receive a second coat. Again, after a corresponding interval, the position of the float is reversed so that it is disposed as in the first stage of the operation and so on until the ends are coated with a sufficient thickness of metal to withstand whatever degree of compression the finished article may be required to sustain.

Obviously the intermediate cylindrical portion of the float will have received a coating of metal about twice as thick as the ends and such intermediate portion will be correspondingly stronger and so able to resist the same compression strains as the ends, despite the fact that due to its form such portion is normally not as strong as the ends.

The successive coatings deposited in this manner of course form one integral shell when the article is finished, as shown in Fig. 2. Furthermore, since there will be more or less splashing of the bath, there will be no sharp line of demarcation between the intermediate thicker portion of the shell and the end portions, but the metal will graduate in thickness so as to give a smooth contour to the external surface of the float.

The electro-deposited coat will adhere di-

rectly to the outer surface of spuds 4 and to the exterior surface of nipple 3. The metal will similarly build up on nipple 6, but the latter will ordinarily be cut off flush with the coat on the adjacent hemispherical end of the float and such end polished off in the final finishing operation. It will be understood, of course, that whichever one of the nipples happens to be immersed, the interior threaded portion of such nipple will be required to be sealed off so as to prevent the deposit of metal therein.

The construction of the float as an article of manufacture forms the subject-matter of our co-pending divisional application filed June 3, 1925, Serial No. 34,620.

Other forms may be employed embodying the features of our invention instead of the one here explained, change being made in the form of construction, provided the steps stated by any of the following claims or the equivalent of such stated steps be employed.

We therefore particularly point out and distinctly claim as our invention:—

1. In a process for making an article of the character described, the steps which consist in partially immersing a suitable core in an electrolytic bath, electro-depositing a metal coating on the immersed portion of such core, then reversing the position of the latter, electro-depositing another coating, and so on until an integral shell of varying thickness is built up, substantially as described.

2. In a process for making an article of the character described, the steps which consist in partially immersing a suitable core of oblong form in an electrolytic bath, one end of such core projecting above the bath, electro-depositing a metal coating on the immersed portion of such core, then reversing the position of the latter so as to leave the other end thereof project above the bath, electro-depositing another coating, and so on until an integral shell is built up having the desired thickness at the respective ends of the core and an increased thickness in the portion intermediate of such ends.

Signed by us this 8 day of November, 1924.

CHESTER C. CLELAND.

JOHN C. MULLINNIX.
